UNITED STATES PATENT OFFICE.

CHARLES B. SMITH, OF CHICAGO, ILLINOIS, ASSIGNOR TO STEWART-WARNER SPEEDOMETER CORPORATION, OF CHICAGO, ILLINOIS, A CORPORATION OF VIRGINIA.

DESIGN FOR A CONSOLE RADIOCABINET.

Application filed March 26, 1926. Serial No. 17,057. Term of patent 7 years.

To all whom it may concern:

Be it known that I, CHARLES B. SMITH, a citizen of the United States, residing in the city of Chicago, in the county of Cook and the State of Illinois, have invented a new, original, and ornamental Design for Console Radiocabinet, of which the following is a specification, reference being had to the accompanying drawings, forming a part thereof.

The drawing is a perspective view of a console radio cabinet embodying my new design.

I claim:

The ornamental design for a console radio cabinet substantially as shown.

In testimony whereof, I have hereunto set my hand at Chicago, Illinois, this 31st day of January, 1926.

CHARLES B. SMITH.
